(57) **CLAIM**

I claim the ornamental design for a door lock and escutcheon, as shown and described.

DESCRIPTION

FIG. 1 is a perspective view of a door lock and escutcheon in a locked configuration with a latch, according to the present design.

FIG. 2 is a perspective view thereof in a locked and chained configuration.

FIG. 3 is a perspective view thereof in an unlocked configuration, according to the present design.

FIG. 4 is a front elevation view thereof.

FIG. 5 is a back elevation view thereof.

FIG. 6 is a left view thereof.

FIG. 7 is a right view thereof.

FIG. 8 is a top view thereof; and,

FIG. 9 is a bottom view thereof.

The door lock and escutcheon is shown with a symbolic break in its length. The appearance of any portion of the article between the break lines forms no part of the claimed design.

The even-length broken lines in the drawings show the remainder of the door lock and escutcheon and form no part of the claimed design.

The dot-dash broken lines in the drawings define the bounds of the claim and form no part thereof.
